C. H. Morris

UNITED STATES PATENT OFFICE.

LORAN LEE HOFFMAN, OF MILWAUKEE, WISCONSIN.

METALLIC SIGNAL FOR LOCOMOTIVES.

Application filed October 30, 1922. Serial No. 597,912.

To all whom it may concern:

Be it known that I, LORAN LEE HOFFMAN, a citizen of the United States, and resident of Milwaukee, in the county of Milwaukee and State of Wisconsin, have invented certain new and useful Improvements in Metallic Signals for Locomotives; and I do hereby declare that the following is a full, clear, and exact description thereof.

10 My invention refers to locomotive signals and it has for its object to provide a simple, economical, and effective combined blizzard lamp and metallic flag for locomotives.

15 The specific object of my invention is to provide a metallic housing for encasing a plurality of selective metallic signal panels adapted to be shifted for exposure, the casing being provided with an integral blizzard lamp.

20 Another object of my invention is to provide a metallic casing having a plurality of metallic signal flags or panels in pivotal union with the casing, whereby one of the flags may be swung to an exposed position,

25 the casing being provided with an integral blizzard lamp.

Another object of my invention is to provide the casing with a removable cover, whereby access may be had to the metallic signal flag units and also to the blizzard lamp.

30 Another object of my invention is to provide means for detachably connecting the metallic housing with the locomotive.

35 With the above and minor objects in view, the invention consists in certain peculiarities of construction and combination of parts, as will be hereinafter set forth, with reference to the accompanying drawings and subsequently claimed.

40 In the drawings:—

Figure 1 represents a front view of a fragment of a locomotive, having attached thereto a combination metallic flag and blizzard lamp embodying the features of my invention.

45 Figure 2 is a similar view of another form of construction of the signal flags, in which the flag may be slidably associated with the casing.

50 Figure 3 is an enlarged plan view of the signal device, as shown in Figure 1, parts being removed and other parts in section, as indicated by line 3—3 of Figure 1.

Figure 4 is a plan view of the signal device having parts broken away to more clearly illustrate structural features.

Figure 5 is a cross section of the signal device, the section being indicated by line 5—5 of Figure 3, and

60 Figure 6 is a sectional view, the section being indicated by line 6—6 of Figure 4, the said section showing particularly the blizzard lamp construction.

Referring by characters to the drawing, A represents the front wall of a locomotive, to which is affixed a strap 1 having a central aperture 2 extending therethrough, which serves as a socket for a leg 3 of a bracket 4, which bracket is secured to the rear wall 5 of a metallic housing. The said housing is preferably formed from a sheet metal blank folded to form a closed end wall 6 and a front wall 7, which is arranged parallel to the rear wall 5, the front wall 7 being provided with a rectangular offset chamber 8, which serves as the casing for a blizzard lamp.

65 The bottom 9 of the housing is preferably provided with drain apertures 10 and the rear end of said housing is open to permit free swing of a pair of metallic panels 11—12, respectively, which panels are pivotally mounted upon a stud 13 that passes through the front and rear walls of the housing, and the panels are suitably spaced by collars, which are mounted upon the stud 13. Thus it will be seen that the metallic panels, which constitute the flag units, can be swung upon their pivot similar to the 85 blades of a jackknife, whereby they may be selectively exposed at the rear end of the housing. These signal panels, or metallic flags, are colored in accordance with standard signal requirements, and the colors are 90 affixed thereto by enamel, whereby they are not dimmed by smoke or weather conditions, and if so, they can readily be cleansed.

95 When it is desired to display a certain signal, for example, panel 12 is swung out, as indicated in Figure 1 of the drawings, to its exposed position with relation to the mouth of the housing, and when the panel is so swung, its lower edge abuts the bottom wall 9 of the housing, whereby the 100 panel will be maintained in its proper exposed position with relation to the housing. After the panel has been so swung to its

exposed position, the housing, which is open at its upper edge, is closed by a removable cover plate 14, which cover plate corresponds in shape to the casing, and it is 5 downwardly flanged at its rear edge and also about the upper edges of the rectangular blizzard lamp casing to thus effectually close the top of the housing against weather conditions. The rectangular off-set cap 10 portion 14' of the cover, which forms a closure for the blizzard lamp casing, has affixed thereto a signal lamp 15, the same being shown in the form of an electric bulb, which extends into the casing, whereby the 15 same is illuminated.

It is understood that the lamp casing or off-set chamber 8 is provided with glass covered apertures or bull's eyes X, through which the light rays are deflected. In order 20 to rigidly hold the slit cover 14 in place, its off-set portion 14', which caps the chamber 8, is provided with a plurality of leaf spring members 16, which frictionally grip the inner walls of the chamber, whereby 25 the cover is rigidly confined and held against displacement, which might otherwise occur, due to vibration.

While I have shown and described the metallic flag units or panels 13 and 14 as 30 being in pivotal union with the housing, they may in some instances be arranged to slide in and out with relation to the casing, as best shown in Figure 2 of the drawing. In this instance, when a selected panel is 35 pulled out, it may be frictionally locked by any suitable means. It will be also noted, as shown in Figures 3 and 4 of the drawings, that the combination metallic housing is set obliquely with relation to the 40 front wall A of the casing, whereby the flag mechanism and its casing, as a whole, will be positioned at an inclined plane with relation to direction of travel of the locomotive, to thus serve as a means for deflecting wind pressure, and any tendency 45 of the flag units to bend or to shift, due to air currents, is eliminated. This anchored position is also desirable where snow conditions are prevalent, to prevent the flag

units from becoming coated with ice or 50 snow and thus obscure the color thereof.

It is also within the scope of my invention to provide the housing and flags in shapes other than rectangular. As for example, the housing and flags might be circular or oval in form without departing from the spirit of the invention.

While I have shown and described several exemplifications of my invention, one of which minutely as to details, it is understood that I may vary the structural features within the scope of the claims.

I claim:—

1. A combination signal for locomotives, comprising a metallic rectangular housing 65 having a lamp casing projecting from its front wall, a removable top cover for the housing and lamp casing, a pair of metallic signal panels in pivotal union with the housing, means for selectively supporting 70 one of the panels in an exposed position with relation to its housing, and a pair of transparent members in said casing respectively adapted to permit light to pass forwardly from said casing and to pass laterally therefrom to illuminate the exposed signal panel.

2. A combination signal for locomotives, comprising a rectangular metallic housing having an open rear end and an open top, 80 a stud extending through the housing near its open rear end, a pair of signal panels in pivotal union with the stud, a slit cover for the rectangular housing and off-set lamp casing, a bracket extending angularly 85 from the rear wall of the housing and having a T-shaped portion, a strap for securing to the front wall of a locomotive, the strap being provided with a T-shaped aperture for receiving the T-shaped portion 90 of said bracket, whereby the housing is supported.

In testimony that I claim the foregoing I have hereunto set my hand at Milwaukee, in the county of Milwaukee and State of 95 Wisconsin.

LORAN LEE HOFFMAN.
